(57) **CLAIM**

I claim the ornamental design for an arcuate guide for intravenous tubes, as shown and described.

DESCRIPTION

FIG. 1 is a perspective view of an arcuate guide for intravenous tubes showing my design;

FIG. 2 is a top plan view thereof;

FIG. 3 is a bottom plan view thereof;

FIG. 4 is a view in rear elevation thereof;

FIG. 5 is a view in front elevation thereof;

FIG. 6 is a right side elevational view thereof;

FIG. 7 is a left side elevational view thereof; and,

FIG. 8 is a perspective view of the arcuate guide guiding an intravenous tube and with a backing panel. The intravenous tube and the backing panel shown in broken lines are for illustrative purposes only and do not form a part of the claimed design.

The broken lines represent environment of use that forms no part of the claim.
